UNITED STATES PATENT OFFICE.

DAVID M. BOLLINGER AND GUSTUS A. SANDERS, OF CAPE GIRARDEAU, MISSOURI.

CURTAIN HANGER.

Application filed October 1, 1920, Serial No. 414,028.

To all whom it may concern:

Be it known that DAVID M. BOLLINGER and GUSTUS A. SANDERS, citizens of the United States, residing at Cape Girardeau, in the county of Cape Girardeau and State of Missouri, have invented certain new and useful Improvements in Curtain Hangers, of which the following is a specification.

This invention relates to shade or curtain 10 hangers or brackets.

It is aimed to provide a novel construction possessing the advantages and characteristics hereinafter described, illustrated in accompanying drawings and then claimed.

15 In said drawings Fig. 1 is a plan view showing a pair of brackets secured to the inner sides of a double window, the latter being shown in transverse section;

Fig. 2, is a front elevation of said 20 brackets;

Fig. 3, is an end view of one of the brackets with the shade-supporting extension detached;

Fig. 4, is a fragmentary end view of the 25 complementary bracket and extension;

Fig. 5, is a view similar to Fig. 1, but showing a modified form of brackets;

Fig. 6, is a front elevation of the brackets used in Fig. 5;

30 Fig. 7, is an end view of one of the brackets of Fig. 5, with the shade supporting extension detached; and

Fig. 8, is a fragmentary end view of the bracket and extension complementary to 35 that of Fig. 7.

Referring specifically to the drawings and first to that form of Figs. 1 to 4 inclusive, A designates the inner sides or stiles of a double window and our improved bracket 40 devices B and C are shown as fastened thereto, it being clear that a device B will be used with device C and that a device C will be used with the device B to make a complete pair of devices for each shade.

45 Each bracket device comprises relatively slidable attaching plates 9 and 10, each having an angle plate or tang 11 provided with struck out lugs or points 12 to enter the wooden frame A. In order to mount plates 50 10 and guide them in their movement, flanges 13 on plates 9 overlap them. Lugs 14 and 15 are struck out from plates 9 and 10 respectively and have openings therein through which a draw bolt 16 passes having 55 a screw type or groove head 17 to bear against lug 14 and a nut 18 which bears

against lug 15 and is held against turning by a stud 19 on lug 15. Portions 20 are struck out from section 10 to support poles or the like which suspend lace curtains or 60 drapery. These portions have recesses 21 to receive the poles and lugs 22 which prevent their escape from the recesses.

Plate 9 is bent flat against tang 11 at 23 and then into angular spacing portion 24 which offsets a shade supporting arm 25 continuing therefrom. One of these arms has an opening 26 which is round to receive the round trunnion of a shade roller, and the other arm has a subrectangular notch 26' to receive and accord in shape with the other trunnion of a shade roller. In instances where the window frame is deep, as in brick buildings, and arms 25 do not locate the shade properly, arms 27 are used, one having a round hole 28 and the other having a substantially rectangular hole 29 conforming to the trunnions referred to. Arms 25 slidably mount arms 27 since flanges 28' on the upper and lower edges of the former overlap the latter as shown.

It is understood that in fastening these brackets, the sections 9 and 10 are placed in slidable relation and the points 12 in engagement with the edges of the stiles A and that the bolt 16 is then tightened to force said points into the wood to support the brackets. A shade may then be placed by inserting the trunnions into the openings of arms 25 or of extensions 27 if the latter are 90 used.

The modified form of brackets shown in Figs. 5 to 8 inclusive, is adapted for use with a single window. In Fig. 5 the sides or stiles of such a window frame are shown 95 at D. The brackets comprise relatively slid- able sections 30 and 31, the latter having the flanges 32 to mount and retain the former. Each section has a tang or plate 33 provided with points or lugs 34, adapted to be forced 100 into the frame stiles D, upon tightening a bolt 35 similar to bolt 16. Bolts 35 pass through lugs 36 and 37 of sections 30 and 31, the latter having a lug 38 to prevent turning of the nut 39. The bolt head is des- 105 signated at 40. Supports 41 similar to sup- ports 20 are struck out from the section 31. From one tang 33 of each plate a spacing plate 42 extends, from which an arm 43 pro- jects at a right angle and which is similar 110 to arm 25 and which slidingly mounts an ex- tension 44 similar to extensions 27, one arm

43 and extensions 44 having round trunnion receiving holes 45 and 46 and the others having substantially rectangular trunnion receiving slots 47 and 48.

5 Since merely preferred embodiments of the invention have been illustrated and described, it is to be understood that changes in the details of construction may be resorted to within the spirit and scope of our invention as defined by the appended claim.

10 We claim:—

A fixture having bracket means for attachment to a support, said means having an angular end portion to engage a side of

the support, a spacing arm extending at substantially a right angle from said end portion and having a shade supporting arm disposed parallel to said end portion, a second shade supporting arm and the latter shade supporting arm being carried slidably adjustable with respect to the first shade supporting arm and disposed parallel to said end portion.

15 20 In testimony whereof we affix our signatures.

DAVID M. BOLLINGER.
GUSTUS A. SANDERS.
